Attorney

UNITED STATES PATENT OFFICE.

WILLIAM V. JOHNSON, OF WASHINGTON, DISTRICT OF COLUMBIA.

BOOKHOLDER.

Application filed September 1, 1927. Serial No. 216,979.

This invention relates to a book holder and it is an object of the invention to provide a device of this kind whereby a book may be readily and conveniently supported in a position

5 to fully comply with the requirements of the reader and which embodies a structure operating to effectively hold the book against accidental displacement.

Another object of the invention is to provide 10 a device of this kind which effectively holds a book in open position and in a manner readily permitting the required turning of the pages but which normally holds the pages of the book against movement.

15 A still further object of the invention is to provide a device of this kind comprising two holding elements supported for movement one with respect to the other and in a manner to automatically compensate for the variance 20 in the back of the book as the pages are turned in order to assure the open book being properly positioned for visual access by the reader.

The invention consists in the details of construction and in the combination and arrangement 25 of the several parts of my improved book holder whereby certain important advantages are attained and the device rendered simpler, less expensive and otherwise more convenient and advantageous for 30 use, as will be hereinafter more fully set forth.

The novel features of my invention will hereinafter be definitely claimed.

In order that my invention may be the 35 better understood, I will now proceed to describe the same with reference to the accompanying drawings, wherein:—

Figure 1 is a view in perspective of a book holder constructed in accordance with an embodiment of my invention;

Figure 2 is a vertical sectional view taken centrally through one of the members of the holder with an intermediate portion broken away;

Figure 3 is an enlarged fragmentary view 45 partly in section and partly in elevation illustrating one of the adjustable leaf engaging members as herein employed;

Figure 4 is a view in perspective of the 50 holder as herein disclosed viewing the same from the rear;

Figure 5 is an elevational view of the rods connecting the members of the holder as herein employed;

55 Figure 6 is a fragmentary view in top plan of one of the members of the holder;

Figure 7 is an enlarged fragmentary sectional view taken substantially on the line 7—7 of Figure 5 with certain of the parts in elevation.

As herein disclosed, my improved holder 60 comprises two members M arranged side by side and which have their opposed vertical edge faces each provided therealong with a groove 1 open at the top.

Interposed between the members M is a pair 65 of cross rods 2 of the desired length pivotally connected midway their ends by a pintle 3. The free extremities of the rods 2 are provided with the spherical heads 4 adapted to be engaged within the grooves 1 whereby the members M are connected one to the other in a manner to permit the same to have movement one with respect to the other and particularly to compensate for books having backs of 70 various thickness, it being understood that when a book is supported by my improved holder the back is freely received between the members M.

The lower portion of each of the members 75 M is provided therealong with a forwardly projecting shelf 5 and overlying the outer portion of said shelf 5 is a plate 6 adjustable toward or from the shelf 5 through the instrumentality of a screw member 7 threaded 80 through the shelf 5 and herein disclosed as having swiveled connection, as at 8, with the plate 6. The upper face of the plate 6 has secured thereto a lamination 9 of yieldable material, such as velvet or plush, which will 85 have yielding contact with the leaf edges of a book without marring or injuring the same.

Each of the members M in its forward or front face and at substantially its center is provided with a dovetail groove 10 in which 90 is snugly engaged a slide member 11, the outer face of which being flush with the outer face of the member M proper. The top of this slide 11 has secured thereto a plate 12 which extends, as at 14, beyond opposite sides of 95 the groove 10 and at its extremities is provided with forwardly directed arms 15. Underlying each of the arms 15 is a plate 16 carrying a lamination 17 of yieldable material for the same purpose as the lamination 100 9 hereinbefore referred to. The plate 16 is adjustably connected to its associated arm 15 through the medium of the screw 18 similar to the manner set forth with respect to the screw.

The pintle 3 rearwardly of the rods 2 is 110 provided with the head 19 with which is

pivotedly engaged an extremity of a rearwardly directed arm 20 having swinging movement in substantially a horizontal direction or in a direction transverse to the members M. The outer end of this arm 20 is fixedly secured to the central part of a cross arm 21. Through each end portion of the arm 21 is freely disposed an arm 22 the inner end of which having a cross head 23 the extremities of which being slidably disposed through the loop members 24 projecting from the rear of a member M. Each of the members M above the cross head 23 is provided with a slot 25 disposed lengthwise of the groove 10 and through which is disposed a headed shank 26 in threaded engagement with the slide 11, the outer end of the shank having a head 27 for contact with the rear face of the member M upon requisite turning movement of the shank to effectively hold the slide 11 in desired adjusted position.

In applying a book to my improved holder, the back of the same is freely inserted between the opposed vertical edges of the members M with the covers of the book clamped between the inner portions of the shelves 5 and plates 12 which is readily accomplished upon requisite adjustment of the slides 11. The plates 6 and 16 are then suitably adjusted to bring the laminations 9 and 17 in proper contact with the leaf edges of the book. The rods 2 permit the members M to be readily adjusted one with respect to the other to compensate for books of various thicknesses and as the leaves of the book are turned the arms 22 will have requisite sliding movement through the arm 21 and the pivotal connection between the arm 20 and the head 19 of the pintle 3 will permit the members M to have forward and rearward movement one with respect to the other to compensate for the variance in the book back in order to maintain the exposed pages of the open book in proper position for visual access by the reader.

My improved holder is adapted to be supported in any desired manner and, as herein disclosed, I indicate a standard S having a forwardly directed extension 28 in universal connection, as as 29, with the central portion of the arm 21 through the medium of a ball and socket joint, a binding screw 30 being associated with such joint in order to effectively hold the desired adjustment as accomplished through the action of this universal joint.

From the foregoing description it is thought to be obvious that a book holder constructed in accordance with my invention is particularly well adapted for use by reason of the convenience and facility with which it may be assembled and operated, and it will also be obvious that my invention is suscep-

table of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. A book holder comprising two members provided with means for engaging the covers of a book with the back of the book positioned between the members, means for connecting the opposed portions of the members for movement one toward the other, and means for connecting said members for relative movement in a forward and backward direction.

2. A book holder comprising two members provided with means for engaging the covers of a book with the back of the book positioned between the members, means for connecting the opposed portions of the members for movement one toward the other, and means for connecting said members for relative movement in a forward and backward direction, said means for engaging the covers of the book being provided with means for frictionally engaging the leaf edges of the book.

3. A book holder comprising two members having grooves in the opposed faces thereof, cross rods having enlargements slidably engaged within said grooves, a member pivotally connecting the crossed portions of the rods, an arm pivotally connected to said member for swinging movement in substantially a horizontal direction, a second arm connected to the outer portion of said first named arm, arms slidably disposed through the extremities of the second arm and provided with cross heads, means for slidably connecting said cross heads to the members, and means for supporting the holder in desired position.

4. A book holder comprising two members having grooves in the opposed faces thereof, cross rods having enlargements slidably engaged within said grooves, a member pivotally connecting the crossed portions of the rods, an arm pivotally connected to said member for swinging movement in substantially a horizontal direction, a second arm connected to the outer portion of said first named arm, arms slidably disposed through the extremities of the second arm and provided with cross heads, means for slidably connecting said cross heads to the members, a supporting stand, and means for adjustably connecting the second named arm with said supporting stand.

In testimony whereof I hereunto affix my signature.

WILLIAM V. JOHNSON.
